Patented May 26, 1959

185,262

COMBINED MAGNETIC TAPE RECORDER AND REPRODUCER

Theodore S. Briskin and Sheldon Lee Pastor, Chicago,
Ill., assignors to Revere Camera Company, Chicago,
Ill., a corporation of Delaware

Application December 27, 1957, Serial No. 49,045

Term of patent 14 years

(Cl. D26—14)

Fig. 1.

Fig. 2.

Fig. 3.

Fig. 4

Fig. 1 is a top plan view of a combined magnetic tape recorder and reproducer, showing our new design;

Fig. 2 is a front elevational view;

Fig. 3 is a side elevational view, the opposite side being substantially a mirror image thereof; and

Fig. 4 is a rear elevational view thereof.

The bottom is free of ornamentation.

We claim:

The ornamental design for a combined magnetic tape recorder and reproducer, as shown and described.
